UNITED STATES PATENT OFFICE.

HYMAN ELI GOLDBERG, OF CHICAGO, ILLINOIS, ASSIGNOR TO GOLDBERG CALCULATING MACHINE COMPANY, A CORPORATION OF ILLINOIS.

CALCULATING-MACHINE.

No. 893,725.

Specification of Letters Patent.

Patented July 21, 1908.

Application filed July 13, 1906. Serial No. 326,081.

To all whom it may concern:

Be it known that I, HYMAN ELI GOLDBERG, a citizen of the United States, residing at Chicago, in the county of Cook and State of Illinois, have invented a certain new and useful Improvement in Calculating-Machines, of which the following is a specification.

My invention relates to calculating machines including calculating attachments to typewriters, and the object of the invention is to provide means whereby the operator may predetermine whether the machine is to add, subtract, or not operate, the actual operation of this controlling device to be automatic or inherent in the machine itself. This invention is not here claimed to be broadly new, as it is shown in a prior patent application for calculating machines filed by me in the United States Patent Office, August 25, 1905, Serial Number 275,780.

Broadly speaking, the invention is also shown in the United States patent applications filed by me December 25, 1905, Serial Number 292,932, and April 21, 1906, Serial Number 313,070.

The distinguishing feature of the present invention relates more particularly to the mechanism by which motion is transmitted from the differential mechanism to the totalizer, and to the mechanism by which said transmission mechanism is operated. In the actual design of the machine here shown, this transmission mechanism consists of gear wheels and means for automatically controlling whether the number of gear wheels in the mechanism shall be an odd or an even number, thereby determining in what direction the totalizer shall operate.

The object of the present invention therefore may be more specifically said to be to provide a particular type of transmission mechanism and controlling means therefor.

I accomplish my object by the mechanism illustrated in the accompanying drawings, in which

Figure 1 is a front view of a typewriter embodying my invention. Fig. 2 is a fragmentary plan view showing the totalizer, totalizer support, transmission gearing, and controlling device. Fig. 3 is a fragmentary front elevation of most of the parts shown in Fig. 2. Fig. 4 is a transverse sectional elevation taken on line 4-4, Fig. 2. In this view the totalizer is shown to be out of operative

connection with the differential mechanism, the transmission gearing being disconnected. Figs. 5 and 6 are similar to Fig. 4, except that in one view an odd number of gear wheels is actively interposed between the differential mechanism and the totalizer, and in the other view an even number of gear wheels is interposed between the differential mechanism and the totalizer. Consequently, in Fig. 5 the action of the differential mechanism will cause, for example, addition, while in Fig. 6 the action of the differential mechanism in the same direction will cause subtraction. Figs. 7, 8 and 9, are vertical sectional views of the controlling pins showing the different effects which may be had upon the controlling portion thereof by turning them to different positions. Fig. 10 is a bottom view of the totalizer showing the controlling cam thereon. Figs. 11 to 18 inclusive illustrate the interior construction of the totalizer. Fig. 11 is a front assembly view partly in section, showing the relation of the different totalizer parts. Fig. 12 is similar to Fig. 11, except that it shows the different pieces spaced somewhat apart to better illustrate their construction. Fig. 13 is a sectional view of the intermediate wheel located farthest to the right in the totalizer. Fig. 14 is a sectional view taken on line 14-14, Fig. 11. Figs. 15 to 18 inclusive are side views of component parts of the totalizer.

Similar numerals refer to similar parts throughout the several views.

This invention might have been embodied in an independent calculating machine, either recording or non-recording. But I have chosen to embody it in a calculating typewriter attachment, and the form of typewriter selected is that of the well-known Remington style in which there is a stationary framework 1, a carriage 2 adapted to travel thereon, and operating keys 3. This present invention is not particularly concerned with the form of differential mechanism employed, and it is sufficient to say that the differential mechanism designated by the numeral 4 is operated by the keys 3 to drive the shaft 5 different amounts depending upon the value of the keys struck. And for use in this connection, a suitable form of differential or digitizing, or valuating mechanism, as it is variously termed in the art, is shown and described in the Patent Number 782,554, issued to me February 14, 110

1905. The totalizer which for the present will be designated in general by the numeral 6 is adapted to travel in unison with the typewriter carriage and has a set of wheels 5 for receiving motion from the actuating mechanism. This actuating mechanism for transmission gearing for transmitting motion from the differential mechanism to the totalizer will now be described, as will also the 10 mechanism for controlling said transmission gearing.

Shaft 5 is adapted to rotate the shaft 7 which is arranged parallel with the travel of the typewriter carriage, and supports and 15 drives the pinions 8, 8. The motion of shaft 5 may be imparted to shaft 7 by means of the bevel gear wheels 9 and 10, or any other suitable connecting devices. Said pinions 8 are concentric with shaft 7 and extend across 20 the machine within the operative limits thereof, as best illustrated in Fig. 1. In the present design said universal pinions are non-traveling, and their axes are fixed, the shaft 7 being journaled in the stationary 25 bracket or platform 11 fastened to the typewriter frame work 1.

A master-shaft 12 having one or more master wheels 13 thereon is journaled in a stationary part of the machine, for example, 30 upon the brackets 14 secured to the platform 11. Said shaft is therefore non-traveling and is rotatable about a fixed axis. Said master wheels are designed to mesh with the totalizer wheels 31 of the totalizer in the 35 manner again to be referred to; and the mechanism for transmitting motion from the universal pinions to the master wheel, which forms one of the features of this invention, will now be described.

40 For the purpose of illustrating the possibility of amplification of the invention and its adaptability to commercial requirements, I have shown a plurality of totalizers and a plurality of master wheels. At each master 45 wheel 13 there is mounted upon platform 11 a slide 14 adapted to move transversely to the direction of travel of the typewriter carriage and totalizer. Any suitable form of guiding means for directing and controlling 50 the sliding movement of said slide upon its platform may be employed, the mechanism here shown being screws 15 screwed or otherwise rigidly secured to the slide 14, and working in slot 16 in platform 11. Mounted 55 in each slide are two transmission gears, one of said gears consisting of a single spur wheel 17, and the other gear consisting of two intermeshing spur wheels 18 and 19.

The actual number of wheels in each gearing is non-essential, the material fact being 60 that in one of said gears there is an odd number of wheels and in the other an even number, so that when one gear is in operation it will produce one effect upon the 65 totalizer, and when the other gear is in

operation it will produce the opposite effect upon the totalizer. Said gear wheels 17, 18 and 19 are so mounted in their slide and the parts are otherwise so arranged and proportioned that when the slide is in one 70 shifted position (shown, for example, in Fig. 5) the single wheel 17 will be in mesh both with the pinion 8 and with the master wheel 13; and when said slide is in the opposite shifted position (shown, for example, in Fig. 6) the wheel 18 will be in mesh with the pinion 8, and the wheel 19 will be in mesh with the master wheel 13. When wheel 17 is in active position, shown in Fig. 5, wheels 18 and 19 are disengaged from 80 wheels 8 and 13, and, conversely, when wheels 18 and 19 are in engagement with wheels 8 and 13, wheel 17 will be out of engagement therewith. In other words, only one kind of gearing is in operation at a time. 85 This would provide for either addition or subtraction, but in order to render it possible for the totalizer to be non-active at a time when its receiving wheels are opposite to a master wheel, it is desirable to arrange for 90 an intermediate position of the slide 14, as shown in Fig. 4, so that when desired, neither the wheels 17 or the wheels 18 and 19 shall be in operative connection between 95 wheels 8 and 13. Such an arrangement is here provided and as a result it is possible to obtain three different conditions, to-wit, action to add, action to subtract, and non-action.

Reference will now be made to the means 100 whereby slide 14 is shifted backward or forward transversely to the path of the totalizer travel. In said slide there are one or more pockets 20, the number of pockets depending upon the number of totalizers to be 105 employed in the machine. It is desirable that each totalizer shall have its own pocket in order that its operation may be independent of all the other totalizers. Each pocket is adapted to receive a controlling 110 piece, the preferred construction whereof is best illustrated in Figs. 7, 8 and 9. As shown there, said controlling pieces consist of a base 21 adapted to fit in said pockets, and upon said base there is a pin 22 adapted 115 to be received within the cam groove 23 upon the bottom of the totalizer, as best shown in Figs. 2, 3, 4 and 10. By preference, said pins 22 are eccentrically located upon their bases 21, and said bases are 120 square in horizontal cross-section, so that they may fit into pockets in any one of three different positions so as to bring the pins 22 at the back, middle, or front of the pockets, as illustrated, respectively, in Figs. 125 7, 8 and 9. In order that the cam 23 upon the totalizer may, by its action upon the pins 22, control the shifted position of slide 14, it is necessary, of course, that said cam should have a fixed path of travel and one 130

reason for mounting the cams upon a totalizer is that the totalizer requiring, as it does, a fixed path in order that the receiving wheels may mesh with the master wheels 13, affords a convenient portion upon which to mount said cams. It will be understood, however, that said cams might be mounted upon some other portion of the machine, so long as the path of the cam remains fixed 10 and it travels in unison with the totalizer. The preferred construction for causing the totalizer to travel in a fixed path and in unison with the typewriter carriage is best illustrated in Figs. 1 and 4, wherein it is shown that said totalizer is rigidly mounted upon a bar 24 rigidly fastened to the brackets 25, which, in turn, are rigidly secured to the slide 26. Said slide is slidably mounted upon the guide bar 27. Bar 27 is arranged 20 parallel with the direction of travel of the typewriter carriage, and is caused to move in unison with the carriage by means of its engagement with an arm 28 depending from the typewriter carriage, as shown in Fig. 1.

25 Although the totalizer *per se* is not here claimed to be new, it being shown and described in my United States Patent No. 782,605, granted February 14, 1905, for a totalizing mechanism, I will briefly describe the construction of said totalizer. It will be understood, however, that other forms of totalizer might be employed, for example, the one shown in Patent No. 741,961, granted to me October 20, 1903. The important thing to be considered in the totalizer is that the wheels acted upon by the master wheels 13 shall be capable of rotating in both directions, one for addition and the other for subtraction.

40 Referring to the totalizer details shown in Figs. 11 to 18 inclusive, 29 represents the totalizer shaft which is non rotatably mounted in the totalizer casing 30. Upon this shaft are supported a plurality of sets or 45 groups consisting of five principal parts, to wit: the receiving or totalizing wheels 31, the carrying pinions 32, the receiving or accumulating wheels 33, the epicyclic pinions 34 and the intermediate wheels 35. Wheels 31, 50 33 and 35 are all freely rotatable about shaft 29 with the exception of wheel 35^a located at the extreme right to correspond with the units column. This wheel is rigid on the shaft and its function is to form a fixed basis 55 or foundation from which the rotatable parts of the totalizer move their definite amounts.

In each group of parts 36 represents a dish like supporting piece which is splined to the 60 shaft and has at its left portion a cylindrical hub 36^a which forms a bearing whereon the intermediate wheel 35 is freely rotatable. The pin 37 extends toward the left from piece 36 and serves as an axle whereon the 65 carrying pinion 32 is freely rotatable. Said

carrying pinion has four long and four short teeth which alternate with each other as best shown in Fig. 12. By means of its teeth said carrying pinion is alternately locked and rotated by the locking ring 31^a and carrying teeth 31^b respectively of the totalizing wheel 31 at its right. The short teeth serve to make the left portion of the carrying pinion a complete eight toothed gear, and this left portion of the carrying pinion remains permanently in gear action with the internal gear portion 31^c of the next totalizing wheel 70 to the left, by means of the gear 33, 34 and 35 hereinafter described. As a result of the carrying action of pinion 32 is always transmitted to the next higher totalizing wheel 31. Each totalizing wheel 31 has a set of numerical figures on its exterior cylindrical surface and is supported by the contact of its internal cylindrical surface 31^a—(which 85 constitutes the aforesaid locking ring) upon the cylindrical edge of the supporting disk 36, said wheels 31 bearing loosely upon their supporting disks so as to be freely rotatable independently thereof.

90 The accumulating wheels 33 are plain spur gears having a comparatively large central aperture so that they may set over and be freely rotatable upon the points of the teeth of the intermediate wheels 35. Said accumulating wheels are narrow and their teeth project beyond the circumference of totalizing wheels 31, so that they may be engaged by the master wheels 13. The totalizing wheel 31^d and supporting piece 36^a (shown 100 at the extreme left of Fig. 11) are slightly modified to impart a finished appearance to the extreme left end of the totalizer.

Extending leftward from each accumulating wheel 33 are two pins 33^a which constitute axles whereon the epicyclic pinions 34 are freely rotatable. Said epicyclic pinions remain in mesh with both the intermediate wheel 35 and the internal gear portion 31^c of wheel 31 for transmitting rotation from one to the other. The aforesaid intermediate wheels 35 are wide faced spur pinions designed to both support the accumulating wheels 33 and also remain in mesh with the carrying pinions 31 and epicyclic pinions 34 at the left and serve to transmit the carrying action of the carrying wheel to the epicyclic pinion and thence to the next higher totalizing wheel 31. As a result of the above described construction of the totalizer it follows that the accumulating wheels 33 are rotatable in either direction and when rotated in one direction will add and when rotated in the opposite direction will subtract.

115 In operation, a pin 22 is so set in its pocket 20 in slide 14 that when the totalizer comes along said slide will be shifted to the front or to the rear or to an intermediate position, depending upon whether the operator desires the totalizer to add, subtract or not 120

operate at that point. If the pin is so set that the approaching cam 23 will throw the slide 14 toward the front, the single wheel 17 will be thrown into mesh with wheels 8 and 13 for transmitting motion in one direction, but if said pin is so set that the slide will be shifted toward the rear then the two wheels 18 and 19 will be thrown into mesh with wheels 8 and 13 and motion in the opposite direction will be transmitted, so that in one position of the slide the totalizer will be made to add, while in the other position of said slide it will be made to subtract, and in an intermediate position no action of the totalizer will occur.

Attention is called to my copending application for patent for calculating machines, filed May 28, 1904, Serial No. 210,158.

What I claim as new and desire to secure by Letters Patent, is:

1. In a calculating machine the combination of a traveling denomination carriage; a totalizer; differential mechanism; gearing for transmitting motion from the differential mechanism to the totalizer; said gearing being arranged in two trains, one having an odd number of wheels therein and the other an even number; and controlling mechanism one portion whereof travels in unison with said carriage whereby the operator may predetermine which of said two sets of wheels in said transmitting gearing shall act.

2. In a calculating machine the combination of a traveling denomination carriage; a reversible totalizer; differential mechanism operating always in the same direction; gearing for transmitting motion from the differential mechanism to the totalizer; said gearing being arranged in two trains, one having an odd number of wheels therein and the other an even number; and controlling mechanism one portion whereof travels in unison with said carriage whereby the operator may predetermine which of said two sets of wheels in said transmitting gearing shall act.

4. In a calculating machine the combination of a totalizer; differential mechanism; gearing for transmitting motion from the differential mechanism to the totalizer; said gearing being arranged in two trains, one having an odd number of wheels therein and the other an even number; and controlling means operated by the totalizer whereby the operator may predetermine which of said two sets of wheels in said transmitting gearing shall act.

3. In a calculating machine the combination of a totalizer; differential mechanism; gearing for transmitting motion from the differential mechanism to the totalizer; said gearing being arranged in two trains, one having an odd number of wheels therein and the other an even number; and controlling means operated by the totalizer whereby the operator may predetermine which of said two sets of wheels in said transmitting gearing shall act.

4. In a calculating machine the combination of a reversible totalizer; differential mechanism operating always in the same direction; gearing for transmitting motion from the differential mechanism to the totalizer; said gearing being arranged in two trains, one having an odd number of wheels therein and the other an even number.

5. In a calculating machine the combination of a totalizer; differential mechanism; gear wheels for transmitting motion from the differential mechanism to the totalizer; said gearing being arranged in two trains, 70 one having an odd number of wheels therein and the other an even number; and means operated by the totalizer for controlling the number, odd or even, of wheels interposed between said differential mechanism and 75 totalizer, to thereby control the direction of action of said totalizer.

6. In a calculating machine the combination of a traveling denomination carriage; a totalizer; differential mechanism; two sets 80 of gear wheels for transmitting motion from the differential mechanism to the totalizer, one of said sets having an odd number of gear wheels therein and the other set an even number; and controlling mechanism one 85 portion whereof travels in unison with said carriage whereby the operator may predetermine which of said sets of transmitting gear wheels shall act.

7. In a calculating machine the combination of a traveling denomination carriage, a 90 totalizer; differential mechanism; two sets of gear wheels for transmitting motion from the differential mechanism to the totalizer, one of said sets having an odd number of 95 gear wheels therein and the other set an even number; and controlling means operated by the totalizer whereby the operator may predetermine which of said sets of transmitting gear wheels shall act one portion of said controlling means traveling in unison with said carriage.

8. In a calculating machine the combination of a traveling denomination carriage, a reversible totalizer; differential mechanism, 105 operating always in the same direction; two sets of gear wheels for transmitting motion from the differential mechanism to the totalizer; one of said sets having an odd number of gear wheels therein and the other set an 110 even number; and controlling means whereby the operator may predetermine which of said sets of transmitting gear wheels shall act, one portion of said controlling means traveling in unison with said carriage.

9. In a calculating machine the combination of a traveling denomination carriage a reversible totalizer; differential mechanism operating always in the same direction; two sets of gear wheels operable at the same 120 point for transmitting motion from the differential mechanism to the totalizer, one of said sets having an odd number of gear wheels therein and the other set an even number, and controlling means operated 125 by the totalizer whereby the operator may predetermine which of said sets of transmitting gear wheels shall act.

10. In a calculating machine the combination of a mas... member; a traveling total- 130

izer having wheels adapted to receive motion from said master member as said totalizer travels past it; a differential mechanism acting always in the same direction; gearing for transmitting motion from the differential mechanism to said master member; said gearing being shiftable into two positions one for producing addition and the other for producing subtraction in said totalizer; and means including a part moving in unison with said totalizer for shifting said gearing into a position preselected by the operator.

11. In a calculating machine the combination of a master member; a traveling totalizer having wheels adapted to receive motion from said master member as said totalizer travels past it; a differential mechanism; gearing for transmitting motion from the differential mechanism to said master member; said gearing having two sets of wheels, one set having an odd number and the other set an even number of wheels and said gearing being shiftable into either of two positions in one of which the set having an even number of gear wheels is interposed between said differential mechanism and master member; and means operated by said totalizer for shifting said gearing whereby the operator may predetermine whether the number of acting pieces in said gearing shall be odd or even.

12. In a calculating machine the combination of a reversible traveling totalizer having wheels adapted to receive motion from said master member as said totalizer travels past it; a differential mechanism operating always in the same direction; gearing for transmitting motion from the differential mechanism to said master member; said gearing having two sets of wheels, one set having an odd number and the other set an even number of wheels and said gearing being shiftable into either of two positions in one of which said gearing produces addition and in the other subtraction in said totalizer; and means operated by the totalizer whereby the operator may predetermine whether the number of acting pieces in said transmission gearing shall be odd or even.

13. In a calculating machine the combination of a reversible totalizer having wheels adapted to receive motion from said master member as said totalizer travels past it; a differential mechanism operating always in the same direction; gearing for transmitting motion from the differential mechanism to said master member; said gearing having two sets of wheels, one set having an odd number and the other set an even number of wheels and means operated by said totalizer whereby the operator may predetermine whether the number of acting pieces in said transmission gearing shall be odd or even.

14. In a calculating machine the combination of a totalizer; differential mechanism, a

gear wheel rotating at each movement of said differential mechanism, another gear wheel adapted to operate said totalizer, two trains of gears, shiftable transversely to their axes for transmitting motion from one of said gear wheels to the other, one of said trains having an even number and the other an odd number of wheels, and means for shifting said trains of gears transversely to their axes to thereby control which one, if either, of said trains of gears shall act.

15. In a calculating machine the combination of a differential mechanism, a traveling totalizer, a gear wheel rotating at each movement of said differential mechanism, another gear wheel in position always to engage and operate the totalizer as the same travels past it, two different trains of gears each operative at the same point of totalizer travel for transmitting motion from one of said gear wheels to the other, in opposite directions, and means for determining which, if either, of said trains of gears shall be operative.

16. In a calculating machine the combination of a differential mechanism, a traveling totalizer, a gear wheel rotating at each movement of said differential mechanism, another gear wheel in position always to engage and operate the totalizer as the same travels past it, two different trains of gears operative at the same point for transmitting motion from one of said gear wheels to the other, in opposite directions, and means operated by the travel of the totalizer for determining which, if either of said trains of gears shall be operative.

17. In a calculating machine the combination of a differential mechanism, a totalizer, having a fixed path of travel, a gear wheel rotating at each movement of said differential mechanism, another gear wheel in position always to engage and operate the totalizer as the same travels past it, two different trains of gears operative at the same point of totalizer travel for transmitting motion from one of said gear wheels to the other, and a cam device part of which is stationary and part of which travels with said totalizer for determining which, if either, of said trains of gears shall be operative.

18. In a calculating machine the combination of a differential mechanism, a totalizer having a fixed path of travel, a gear wheel rotating at each movement of said differential mechanism, another gear wheel in position always to engage and operate the totalizer as the same travels past it, two different trains of gears for transmitting motion from one of said gear wheels to the other, and means for determining which, if either, of said trains of gears shall be operative, said determining or controlling means consisting of a stationary pin and a cam traveling in unison with said totalizer and adapted to act upon said pin.

19. In a calculating machine the combination of a differential mechanism, a totalizer, having a fixed path of travel, a gear wheel rotating at each movement of said differential mechanism, another gear wheel in position always to engage and operate the totalizer as the same travels past it, two different trains of gears both operative at the same point for transmitting motion from one of 5
10 said gear wheels to the other, and means for determining which, if either, of said trains of gears shall be operative, said determining or controlling means consisting of a stationary pin adapted to be adjusted to different operative positions, and a cam traveling in 15 unison with said totalizer and adapted to act upon said pin.
20. In a combined typewriter and calculating machine the combination of a traveling typewriter carriage, a stationary supporting frame, a typewriter key action supported in said frame, a totalizer having a fixed path of travel and traveling in unison with said carriage, a differential mechanism 25 operated by said key action, two alternate sets of gearing operative at the same point and in opposite directions for transmitting motion from the differential mechanism to the totalizer, and controlling means one part 30 whereof travels in unison with said carriage whereby the operator may predetermine which set of said transmission gearing shall be operative.
21. In a combined typewriter and calculating machine the combination of a traveling typewriter carriage, a stationary supporting frame, a typewriter key action supported in said frame, a totalizer traveling in unison with said carriage, and having a set 35 of receiving wheels side by side for operating said totalizer, a non traveling master wheel for operating said receiving wheels of the totalizer as the same travels past it; a differential mechanism two alternate sets of 40 gearing for transmitting motion from the differential mechanism to the totalizer and operative in opposite directions at the same point of action and a controlling device whereby the operator may predetermine 45 which set of said transmission gearing shall be operative.
22. In a combined typewriter and calculating machine the combination of a traveling typewriter carriage, a stationary supporting frame, a typewriter key action supported in said frame, a totalizer traveling in unison with said carriage, and having a set 55 of receiving wheels side by side for operating said totalizer, a non traveling master wheel for operating said receiving wheels of the totalizer as the same travels past it; a differential mechanism, two alternate sets of 60 gearing for transmitting motion from the differential mechanism to the totalizer in opposite direction and at the same point 65 of action and a cam device for throwing one or the other of said alternate sets of gearing into connection between said differential mechanism and master wheel, at the selection of the operator. 70
23. In a combined typewriter and calculating machine the combination of a traveling typewriter carriage, a stationary supporting frame, a typewriter key action supported in said frame, a totalizer traveling in 75 unison with said carriage, and having a set of receiving wheels side by side for operating said totalizer, a non traveling master wheel for operating said receiving wheels of the totalizer as the same travels past it; a differential mechanism two alternate sets of 80 gearing for transmitting motion from the differential mechanism to the totalizer, in opposite directions and at the same acting point, a slide movable transversely to the 85 axis of said master wheel for carrying said two alternate sets of gearing, and a cam device for operating said slide to throw one or the other of said sets of gearing into operative connection. 90
24. In a combined typewriter and calculating machine the combination of a traveling typewriter carriage, a stationary supporting frame, a typewriter key action supported in said frame, a totalizer traveling in unison 95 with said carriage, and having a set of receiving wheels side by side for operating said totalizer, a non traveling master wheel for operating said receiving wheels of the totalizer as the same travels past it; a differential mechanism; two alternate sets of gearing for 100 transmitting motion from the differential mechanism to the totalizer, a slide movable transversely to the axis of said master wheel for carrying said two alternate sets of gearing, and a cam device part of which is stationary and part of which travels in unison 105 with the typewriter carriage for operating said slide to throw one or the other of said two sets of transmission gearing into operative connection. 110
25. In a combined typewriter and calculating machine the combination of a traveling typewriter carriage, a stationary supporting frame, a typewriter key action supported 115 in said frame, a totalizer traveling in unison with said carriage, and having a set of receiving wheels side by side for operating said totalizer, a non traveling master wheel for operating said receiving wheels of the totalizer as 120 the same travels past it; a differential mechanism two alternate sets of gearing for transmitting motion from the differential mechanism to the totalizer, a slide movable transversely to the axis of said master wheel for 125 carrying said two alternate sets of gearing, and a cam device for operating said slide to thereby enable the operator to select which of said sets of transmission gearing shall be operative, said cam device including a cam. 130

and a pin, the pin being hand adjustable, substantially as described.

26. In a calculating machine the combination of a traveling denomination carriage; a differential mechanism rotating always in the same direction; a totalizer; a train of transmission gears including a shiftable member the shifted position whereof determines the direction of transmission; and means including a part traveling in unison with the denomination carriage for shifting said shiftable member of the train of transmission gears.

27. In a calculating machine the combination of a traveling denomination carriage; a differential mechanism rotating always in the same direction; a totalizer; a double train of gearing for transmitting motion from said differential mechanism to said totalizer, said 15 transmission gearing being shiftable into two positions, in one position for addition and the other position for subtraction; and a cam device including a part traveling in unison with

the denomination carriage for shifting said gearing into its different positions at the operation of the operator.

28. In a calculating machine the combination of a traveling denomination carriage; a differential mechanism rotating always in the same direction; a totalizer; two trains of 20 gearing for transmitting motion from said differential mechanism to said totalizer, said trains being shiftable so that only one shall be operative at a time and said trains being adapted to transmit motion in opposite directions; and a cam device including a part traveling in unison with the denomination carriage for shifting said transmission trains.

In witness whereof, I have hereunto subscribed my name in the presence of two witnesses.

HYMAN ELI GOLDBERG.
